UNITED STATES PATENT OFFICE.

EDMUND A. LOKEY, OF CLAY COUNTY, GEORGIA.

FERTILIZER MIXER.

Application filed September 3, 1925. Serial No. 54,267.

The object of this invention is to provide a simple apparatus whereby the several fertilizer materials may be properly proportioned and thoroughly mixed and reduced to a s 5 desired fineness and delivered direct to a sacker, as more fully hereinafter set forth.

In the drawings—

Fig. 1 is a plan view of my apparatus;

Fig. 2 is a side elevation thereof;

Fig. 3 is an end elevation of my apparatus;

Fig. 4 is a vertical sectional view taken through the mixing-cylinder;

Fig. 5 is a longitudinal sectional view of the mixing-cylinder detached.

In the drawings annexed, 10 designates the imperforate section of the mixing-cylinder and 11 the perforated or reticulated or screen section of the cylinder, this cylinder 20 being affixed to a supporting shaft 12 by means of a series of spiders 13, one being placed at the upper, inlet end of the cylinder, another at the point where the imperforate cylinder joins the screen section, and 25 the remaining one at the exit end of the screen section. The shaft and its cylinder incline downwardly from the inlet to the outlet end of the cylinder, so that the fertilizer materials, when delivered into the forward end of the cylinder and the cylinder 30 is revolved, will gravitate toward the lower, exit end.

The fertilizer materials, properly proportioned, are delivered, by gravity, into the upper end of the cylinder by means of a chute 14 which projects into the inlet-end of the cylinder to a distance short of the first spider 13. The extreme upper end of the section 10 of the cylinder, i. e., that portion which projects above the said spider 13, is curved inwardly at 15 to form a dam which functions to prevent spilling at this inlet-end of the cylinder. The fertilizer materials are mixed and broken up in the 45 imperforate section 10 as the cylinder rotates, and the materials are finally delivered onto the screen section 11 which serves not only to further mix and break up the lumps but also to screen out the materials 50 that have been reduced to a sufficient fineness to pass through the screen. The screened and mixed materials drop into a chute 16 whose upper end partly surrounds the screen section, and thence through a downwardly-inclined spout 17 to a sacker 18 mounted at one 55 side of the frame of the apparatus. The

spiders, by cutting through the mass of fertilizer materials, serve to assist in breaking up the lumps. The lumps that are not broken up and are too large to gravitate through the screen 11 pass out through the final spider 60 and drop into a hopper 19 of a crusher of any suitable construction; thence the crushed lumps are delivered, by means of a short inclined chute 20, into the final delivery 65 chute 17, to be mixed with the materials that have come down through the screen. This crusher is driven by means of a belt 21 which in turn is driven by a pulley on the main drive-shaft 22 extending across the lower end of the machine frame. The final spider 13 is provided with an inwardly-extending annular flange 23 which serves as a dam for holding the fertilizer materials until they have been well jumbled in the 70 screen section of the cylinder, so that only the lumps shall pass over into the crusher.

The cylinder is driven by means of a sprocket-wheel 24 forming part of the final spider, the sprocket-chain 25 for this wheel being driven by a sprocket-wheel affixed to a counter-shaft 26 journaled on the frame and extending substantially parallel with the screen section of the cylinder, this counter-shaft being driven by bevel-wheels 27 on the 75 main drive-shaft 22. This counter-shaft 26 is provided with a pulley 28 which is belted to the conveyor-member of the sacker 18 to thereby continuously actuate the sacker mechanism while the sacker is being filled 80 from the spout 17.

The inlet-spout 14 is connected with the outlet 29 of a hopper 30. This hopper 30 is a large rectangular trough or box open throughout its upper surface. The outlet 95 29 is formed in the wall of this box that is adjacent to the mixing-cylinder. A gate 31 extends across this hopper or box at one side of the outlet 29. This gate is mounted to slide in vertical ways 32 attached to the walls of the box. A similar set of ways 32 is arranged at the opposite side of the outlet 29. The purpose of this specially designed hopper is as follows: While the materials that are in that section of the box which is in communication with the outlet 29 are being raked or shoveled through the outlet 29 into the chute 14, the fertilizer materials are being placed in the other, cut-off section of the hopper in layers, the various materials having been previously weighed. After one section of the hopper has 100 105 110 115

- thus been emptied into the mixing-cylinder, the gate 31 is shifted over to the other guides 32 to thus open up the previously-filled section, to thereby permit the materials placed therein in layers to be shoveled or raked out through the outlet 29. While this is being done, of course the fertilizer materials are being properly placed in the other hopper. By means of this hopper, therefore, the materials may be not only properly proportioned and distributed with reference to each other over a considerable area, but the process of feeding the mixing-cylinder may be continuously carried on.
15. What I claim as new is:
1. In a mixing apparatus, a mixing and grinding cylinder mounted on a shaft and having its lower end provided with a cylindrical screen, an external sprocket-wheel carried by the cylinder at its delivery-end, this sprocket-wheel being open and provided with an annular flange extending inwardly to form a lump-dam, a lump-grinder having its hopper positioned to receive the lumps as they roll over said dam at the rear, lower end of the cylinder, a sprocket-chain for driving said cylinder through said sprocket-wheel, and means for driving said sprocket-chain and also said lump-grinder.
  2. In a fertilizer-mixing machine, a mixing mechanism and a hopper at the inlet end thereof, said hopper consisting of an open box having an exit midway one of its walls, and a gate extending across the hopper and means whereby this gate may be placed at either side of said exit, for the purposes set forth.
  3. In a fertilizer-mixing apparatus, a cylinder having an imperforate entrance-section and a screen-section at the delivery end, means for driving the cylinder embodying an external sprocket-wheel carried by the cylinder at its delivery-end, this sprocket-wheel being open and provided with an annular flange extending inwardly to form a lump-dam, a lump-grinder having its hopper positioned to receive the lumps as they roll over said dam at the rear, lower end of the cylinder, a sprocket-chain for driving said cylinder through said sprocket-wheel, and means for driving said sprocket-chain and also said lump-grinder.
- In testimony whereof I hereunto affix my signature.

MILTON A. LOKEY.
